Attorneys

UNITED STATES PATENT OFFICE.

CORYDON G. SNYDER, OF OAK PARK, ILLINOIS.

CHART FOR MEMORIZING WIRELESS CODES.

Application filed December 12, 1922. Serial No. 606,423.

To all whom it may concern:

Be it known that I, CORYDON G. SNYDER, a citizen of the United States, residing at Oak Park, in the county of Cook and State 5 of Illinois, have invented certain new and useful Improvements in Charts for Memorizing Wireless Codes, of which the following is a specification.

This invention relates to improvements in 10 charts for memorizing purposes.

The primary object of this invention is the provision of a chart, primarily adapted for use in connection with the memorizing of codes.

15 A further object of this invention is the provision of a chart for code memorizing, embodying code signs arranged in such distinctive manner as to at once suggest the character which they represent.

20 A further object of this invention is the provision of a chart for code memorizing, having certain characters delineated thereon, and the code signs symbolic of the same arranged in contrasting conforming relation therewith, whereby a pupil may in a minimum of time memorize the respective code symbols of the characters, and recall the arrangement of signs of the code symbols with comparative ease.

25 A further object of this invention is the provision of a chart of the above mentioned character, embodying a novel arrangement of code signs symbolic of a certain set of characters, so co-related that the code signs of certain characters are suggestive of the code signs of other characters.

30 Other objects and advantages of this invention will be apparent and inherent in the following detailed description.

35 In the drawing wherein for the purpose of illustration is shown but the preferred embodiment of this invention, a set of alphabetical characters are depicted, showing the international wireless code symbols for the same, and in addition showing the alphabetical characters and the contrasting conforming relation of the respective code symbols thereof.

40 In the drawing, wherein for the purpose of illustration is shown the chart in its preferred embodiment, the numeral 10 designates a set of characters, such as the letters of the alphabet, which preferably have code signals 11 symbolic of the same disposed therebelow. These symbols 11 are

preferably the international wireless code symbols, and show the arrangement of the dot and dash signs 12 and 13 of said symbols for the respective characters of the set 10.

45 The novelty in the improved chart consists in the association of the characters or letters 10 and their symbols 11, as to instantly impress upon the mind of the person the signs of the various symbols. To this end, the set of characters or letters 10 are each finely delineated on the chart, as designated by numeral 15, and the respective code signs of the characters are superposed in heavy relation upon the fine outline 50 of the characters, so as to have the dot and dash code signs of said symbols stand out distinctively, and contrastingly on the form of the character which they represent.

55 This novel association of the characters and the symbols therefore may be effected as indicated in the illustration of the improved chart, whereby the character or letter is finely outlined with the signs of the code symbol heavily depicted in superposed 60 contrasting relation thereon. A similar effect may be had by contrasting, in different colors, the character and its respective code symbol, and other means of contrasting the code symbol and its character in associated 65 manner may suggest themselves.

70 There are four outstanding mechanical features by means of which the pupil is aided in memorizing and directly recalling the character of a code symbol, and vice 75 versa, which are as follows:

75 First, The code signs which symbolically designate a particular character are arranged substantially in the form of the character which they represent.

Second, The code signs symbolic of the characters are delineated in superposed relation with the character which the code signs represent.

80 Third, The code signs of the various code symbols are arranged substantially in the form of the character which they represent, and are readable in a continuous direction along the form of the character.

85 Fourth, The code signs are arranged in groups or symbols, and in the form of the character each group represents, in such manner that the arrangement of code signs of one character is suggestive of the arrangement of code signs of other characters. 90

From the foregoing it can readily be understood that the code signs and symbols are directly associated with the character or letter which they represent. Thus, in the memorizing of the signs of the various code symbols, there are no words or phrases which must first be learned, as is necessary in most methods, systems, and charts for instruction of codes and the like. It is thus evident that the simplicity of the characters and their respective code symbols as taught by the improved chart, is an advantage over any means of memorizing a code which necessitates the memorizing of words and sentences in order to recall the code symbols of letters and vice versa. The basic principle is the direct co-relation between the shape of the character or letter, and the code symbol representative of that character, which is associated in conforming relation with the character. Therefore, to recall the symbol for any certain character, it is only necessary to recall the shape of the character or letter itself.

Referring again to the fourth mechanical feature enumerated above, wherein a relation is established between certain characters having somewhat similar shapes and code symbols. In connection with the chart illustrated in the drawing, instructions may be forwarded the student either on the chart or on separate pamphlet, calling the student's attention to the similarity of certain characters and the code symbols thereof.

Thus, in connection with the letter A, the following note can be given:

"On A the horizontal bar is used for the dot and the slanting line on the right for the dash. Thus, we read from left to right: dot, dash. The central line of B, E, F, and H are also used for dots."

For the letter F, the following note may be given:

"With F we start by using the top line for two dots, then the upright for the dash, and the central line for the final dot. When we consider that L, is nearly the same shape inverted and that the code signals are just the reverse, the two are very easily remembered."

For the letter S the following note may be given:

"S is easily remembered by itself or with B and D or even O. Nearly everyone knows that the distress call is S O S. And as S has three dots and O three dashes, the two are easily remembered by this, if for no other reason."

It can readily be understood from the foregoing that notes may be used in connection with each letter, which while not necessarily serving as a part of the chart, may serve to call the attention of certain inapt students to the relation of the various characters and the various symbols. Of

course, the ease of memorizing the code by means of the improved chart is based upon certain physiological principles, and for some students no great effort of study will be required, and the notes in connection with the various characters may be dispensed with altogether.

The word character as used in this specification and the claims thereof is to be given a broad meaning, and may be interpreted to designate letters of the alphabet, numerals, punctuation marks, writing, printing, or other indicia.

It is to be noted that the dots have been designated on the chart as short strokes at an inclination to the vertical. This is done in order to facilitate code writing by the pupil, as it is more convenient to scribe a dot in the manner illustrated, and makes the dot more distinctive than if a round true dot were shown.

Features of the improved chart are of course susceptible of use in various other ways than that herein described and illustrated. It is contemplated to utilize the features of the improved chart in connection with memorizing, translating, interpreting, etc., of various languages, studies, systems, and codes. Such changes will of course be made without departing from the spirit of the invention or the scope of the claims.

I claim:

1. A chart for code memorizing comprising code delineations arranged substantially in the form of the characters they represent. 100
2. A chart for code memorizing comprising a plurality of groups of code delineations symbolic of certain characters, the code delineations of each group being arranged substantially in the outline of the characters said group represents. 105
3. A chart for code memorizing comprising characters, and the code symbols of said characters, said characters and their respective code symbols being disposed in distinctive superposed relation. 110
4. A chart for code memorizing comprising finely outlined characters, and code symbols representative of said characters distinctively displayed on said outlined characters. 115
5. A chart for code memorizing comprising finely outlined characters, and code delineations representative of said characters heavily displayed in conforming and contrasting relation with their respective characters. 120
6. A chart for code memorizing comprising a set of characters, and dot and dash code symbols for said characters contrastingly superposed on said characters. 125
7. A chart for code memorizing comprising a set of characters, and International 130

wireless code symbols therefor displayed in distinctive outlining relation with said characters.

8. A chart for code memorizing comprising characters, and code symbols representative of said characters displayed in contrasting outlining relation with their respective characters and readable in a continuous direction along said characters.

10 9. A chart for code memorizing comprising characters, and code symbols for said characters disposed in superposed relation with said characters, said code symbols of said characters being readable in a continuous direction along said characters.

10. A chart for code memorizing comprising a set of characters, and International wireless code symbols representative of the several characters in said set, disposed in superposed relation therewith, symbols of certain characters being readable in a continuous direction along said characters. 20

11. A chart for code memorizing comprising code signs arranged in groups and in the form of the character each group represents in such manner that the arrangement of code signs of one character is suggestive of the arrangement of code signs of other characters. 25

CORYDON G. SNYDER.
